UNITED STATES PATENT OFFICE.

PATRICK J. McGRATH AND JOHN W. HALLOWELL, OF BROOKLYN, NEW YORK.

GAME APPARATUS.

1,117,136.

Specification of Letters Patent. Patented Nov. 10, 1914.

Application filed September 8, 1914. Serial No. 860,589.

To all whom it may concern:

Be it known that we, PATRICK J. McGRATH and JOHN W. HALLOWELL, citizens of the United States, and residents of Brooklyn, in the county of Kings and State of New York, have invented certain new and useful Improvements in Game Apparatus, of which the following is a specification.

10 This invention relates to improvements in game apparatus and its main object is to provide improved mechanism for casting small projectiles to varying distances, and another object is to provide means for keeping count of the throws in the game.

15 The means we employ for accomplishing these results, together with full details of our improved game apparatus, are illustrated in the accompanying drawing, in which,—

20 Figure 1 is a side elevation of the preferred form of our invention. Fig. 2 is a plan of the same. Fig. 3 is a front elevation of the same. Fig. 4 is a side elevation 25 of a modified form of our invention. Fig. 5 is a side elevation of the same.

Like characters of reference designate like parts in all figures of the drawing.

In Figs. 1, 2 and 3, the numeral 2 designates the frame of the apparatus, said frame being of rectangular outline and provided with flanges 3. A spout 4 is fastened to the frame at one end, and extends upward for some distance, and is also inclined several degrees from the vertical, so as to lean toward the central portion of the apparatus.

40 A horizontal member 5 is supported by the spout 4 at one end, and connected by struts 6 to the frame at the other end. Primary projectile receivers 7 are carried by the member 5, and any convenient number can be provided, but five is the preferred number. Said projectile receivers are cylindrical in section and their height is two or three times their diameter. They are open at the top and provided with inclined bottoms 8, and outlets 9, so that spherical projectiles will roll out through said outlets.

50 A lever support 10 is mounted on the frame 2, and a finger lever 11 is pivoted thereon by the pivots 12. The free end 13 of the lever is inserted into an opening 14 in the spout 4, and normally rests in the full line position, as shown in Fig. 1.

At one side of the primary projectile receivers, and on the lower part of the frame, immediately under the outlets 9 are secondary projectile receivers 15, which are rectangular compartments, open at the top and numbered as in the plan. These numbers are used in marking the scores in playing the game, and the lowest is nearest the spout and the higher ones are placed in order as the distance from the spout increases.

The operation of our improved game is as follows: A spherical projectile, such as a rubber ball or a marble P is placed on the end 13 of the finger lever 11. The player 70 then presses down the finger end 16 of the lever, causing the projectile to fly upward through the spout and emerging, takes a curved path into one of the projectile receivers, if the proper skill is exercised. 75 Greater skill of course is required to score the higher numbers and not throw beyond the last receiver. As the projectile enters one of the primary receivers and reaches the inclined bottom, it passes out through the 80 outlet 9 into the secondary receiver beneath, on which is indicated the proper score number.

In the modified form of our invention illustrated in Figs. 4 and 5, the base 2, 85 spout 4, lever support 10, lever 11, and pivots 12 are like those in the form just described.

The secondary projectile receivers are omitted however, and the primary receivers 90 are supported on a platform 20 held up by side supports 21. A slide 22 is fastened to the lower face of the platform 20 by means of clips 23. Said slide is provided with openings 24, and the projectile receivers are 95 provided with bottom openings of the same size, so that when the slide is moved endwise of the platform a short distance the openings 24 will come opposite the openings in the bottom of the said projectile receivers, 100 allowing any projectiles in the receivers to fall through, down onto the frame. The projectile receivers are marked with the proper numbers for scoring, and the game is played with this form in the same manner 105 as with the first described construction.

We claim:

1. In a game apparatus, the combination of an inclined spout, and a finger lever pivoted below the spout and adapted to force 110 projectiles through the spout to varying distances.

2. In a game apparatus, the combination of a frame, an inclined spout mounted on the said frame, a finger lever pivoted on said frame and adapted to force projectiles through said spout, to varying distances, and two or more projectile receivers mounted on the frame, each at a different distance from the said spout.

3. In a game apparatus, the combination of a frame, an upwardly inclined spout mounted on said frame, a finger lever pivoted on the frame and adapted to force projectiles upward through said spout by depressing the finger end of said lever, and two or more projectile receivers mounted on the frame in line with spout and the lever, and at different distances from the said spout.

4. In a game apparatus, the combination of a frame, an upwardly inclined spout mounted on said frame, a finger lever pivoted on said frame and adapted to force projectiles upward through said spout to varying distances, and two or more projectile receivers mounted on said frame, each at a different distance from the spout and each having an opening at the top and a lower projectile outlet.

5. In a game apparatus, the combination

of a frame, an inclined spout mounted on said frame, a finger lever pivoted on said frame and adapted to force projectiles upward through said spout to varying distances, a plurality of primary projectile receivers mounted on the frame in line with the spout and the lever, each at a different distance from the spout and each provided with an inclined bottom and a lower outlet, and a plurality of secondary projectile receivers located so as to receive the projectiles from the primary receivers.

6. In a game apparatus, the combination of a frame, an inclined spout mounted near one end of said frame, a finger lever having one end located in the lower part of the spout, having a finger portion near the other end of the frame, and pivoted at an intermediate point, and two or more projectile receivers mounted on the frame above the lever, in line with each other and the spout.

Signed at New York, in the county of New York and State of New York, this 28th day of August, A. D. 1914.

PATRICK J. McGRAH.
JOHN W. HALLOWELL.
